UNITED STATES PATENT OFFICE

EDWARD E. THISLER, OF HARRODSBURG, KENTUCKY

ROTARY SINGLE SLEEVE-VALVE MOTOR

Application filed May 7, 1928. Serial No. 275,822.

This invention aims to provide a novel internal combustion engine in which the piston is mounted for reciprocation in a rotary valve, novel means being provided for rotating the 5 valve, and the valve having a single port which serves both as an admission port and an exhaust port. Another object of the invention is to provide novel means for reciprocating the working parts. Other advantages will be made manifest hereinafter, and it will be understood that a mechanic, working within the scope of what is claimed, may make changes without departing from the spirit of the invention.

15 In the drawings:—

Figure 1 is a longitudinal section of the engine;

Figure 2 is an elevation of the valve;

Figure 3 is a cross section on the line 3—3 20 of Figure 1.

The crank case 1 includes a base 2 and a body 3 joined together by bolts 4, or otherwise, and having bearings 5 in which the crank shaft 6 is journaled, the crank appearing at 7. At its upper end, the body 3 of the crank case has a thickened portion 8 in which is formed an annular oil chamber 9 having an outlet 10 which discharges into the crank case 1. The upper end of the body 3 of the crank case 1 is supplied with an inwardly projecting flange 11, and above the flange 11 there is a gear compartment 12 in the upper end of the body 3 of the crank case.

The cylinder is designated by the numeral 35 14 and is surmounted by a cap 15 held in place by securing elements 16, the cap having a central extension 17, the extension being spaced from the cylinder wall to give room for the rotary valve hereinafter described.

40 The cap 15 and the cylinder 14 are water jacketed as at 18, in any suitable way, and in order to remove the water from the cap or head 15 when the water is drained out of the jacket of the cylinder 14, a U-shaped siphon pipe 19 is provided, one end of the siphon pipe 19 extending downwardly into the water jacket of the engine head, and the other end of the siphon pipe extending downwardly into the water jacket of the cylinder, 45 as shown in Figure 1. The head 15 of the

engine has a depressed portion 20 in which is mounted a spark plug 21, the spark plug projecting downwardly into an inverted funnel shaped opening 22 in the cylinder head ing, the opening 22 communicating with the 55 combustion chamber of the engine.

It will be understood that any suitable means for firing the engine may be provided, the spark plug 21 being typical of any suitable means for igniting the charge. The cylinder 14 is provided near to its lower end with an outstanding annular foot 23 which is connected to the thickened portion 8 of the crank case by means of securing elements 24. The lower end of the cylinder 14 extends 60 downwardly into the gear compartment 12, as shown at 25. The cylinder 14 is equipped near to its outer end with oppositely disposed ports 26 and 27.

There is a worm chamber 28 in the thick- 70 ened portion 8 of the crank case, and the lower portion of the cylinder 14 has an open- 75 ing 29 which communicates with the worm chamber. A shaft 30 is supported for rotation in the engine frame and carries a worm 31 located in the worm chamber 28. The shaft 30 is driven from the crank shaft 6 in any suitable way, for instance, by means of a chain drive 32 indicated in Figure 1.

A sleeve valve 33 is journaled for rotation 80 in the cylinder 14, the upper end of the valve 33 being rotatably mounted between the cylinder wall and the extension 17 of the cylinder head, the extension 17 carrying a pack- 85 ing ring 34 which cooperates with the inner surface of the valve 33. The lower end of the valve 33 rests on the flange 11 of the crank case and has a pinion 35 which extends through the opening 29 in the cylinder 14 and 90 engages with the worm 31, so that when rotation is imparted to the worm, rotation will be transmitted to the valve 33.

The valve 33 has a single port 36, so located 95 as to register with the ports 25 and 26 of the cylinder. Around the port 36, in the outer surface of the valve 33, there are grooves 37 adapted to hold oil, thereby to form a seal around the port 26. Above and below the port 36, the valve 33 is provided with circum- 100 ferential oil grooves 38—48. A pitman 39

is pivotally connected with the crank 7, in the usual way, and is pivoted to a piston 40 which is mounted for reciprocation in the valve 33.

5 The lubricating system for the engine is simple but highly effective. It comprises a gear pump 41 mounted within the base 2 of the crank case 1 and operated by a shaft journaled in a bearing 42 mounted on the crank case, the aforesaid shaft being connected to the crank shaft 6 by bevelled gears 43, the shaft being connected with the pump 41 by bevelled gears 44. The pump 41 takes oil out of the crank case and forces it upwardly 10 through a pipe 45. The pipe 45 has a branch 46 which delivers oil into the worm chamber 28. From the worm chamber 28, the surplus oil is delivered back into the crank case 1 through the outlet 10. The pipe 45 has a lateral branch 47, and by means of this branch, oil is delivered into the grooves 48 of the valve 33. At its upper end, the pipe 45 has a branch 49 by which oil is delivered into the grooves 38 of the valve 33. In the midst of the grooves 38 there is an opening 50 in the valve 33, the opening 50 being disposed opposite to the branch 49.

By this construction, oil is admitted inside of the upper end of the valve 33, and the valve is lubricated, where it turns on the central extension 17 of the cylinder head 15. The oil in the grooves 48 of the valve 33 can find its way into a spiral groove 51 formed in the outer surface of the valve 33 and extended downwardly to the pinion 35. By means of the groove 51, the outer surface of the valve 33 is lubricated, between the grooves 48 and the pinion 35. Any desired number of openings 52 are formed in the wall of the valve 33, these openings communicating with the interior of the valve 33. By means of the openings 52, surplus oil is delivered inside of the valve 33 and back into the crank case. By means of the groove 51, some oil is delivered upon the gear 35, but the gear gets most of its oil from the worm chamber 28, into which the oil is delivered by the branch 46. The oil in the gear compartment 12 is kept at a constant level because there is an opening 53 in the 10 part 8 of the crank case, the opening 53 being located a sufficient distance above the flange 11. In general operation, the piston 40 reciprocates in the valve 33, the port 36 of the valve coming into registration with the ports 26 and 27 of the cylinder, to admit the charge and to let out the exhaust gases. The valve 33 is rotated, to bring the port 36 into and out of registration with the ports 26 and 27, as aforesaid, through the instrumentality of the 15 worm 31 which meshes with the gear 35 on the lower end of the valve 33, the worm 31 being operated from the crank shaft 6 by way of the chain drive 32.

The device forming the subject matter of this application is of the rotary single sleeve

valve type, the valve being provided with a single port, and the invention may be embodied in any four cycle internal combustion engine. The device is characterized by extreme simplicity, in that there are practically no more than two moving parts in each cylinder, to wit, the valve 33 and the piston 40. The rotary valve 33, with its single port 36, has many advantages over valves of a different kind: for instance, since the valve has but one port, the chances of loss of compression is avoided. The gases from the carburetor serve to cool and keep clean the edges of the port 33 in the valve. The port 36 is at approximately ninety degree positions when the intake and exhaust is effected, as shown in Fig. 3, and, consequently, the combustion chamber is sealed against leakage. The general construction of the engine is such that the bad effects of the hot exhaust gases are cut down to a minimum. The sleeve valve 33 is so constructed that it can be machined and accurately constructed, thereby rendering it possible to secure lubrication with a minimum amount of oil. The valve 33 rotates at one half the speed of the crank shaft 6 and the valve, therefore, will be kept true and round, both inside and out, thus providing for snug fit of the valve within the cylinder 14, and about the piston 40. One of the great advantages of the valve 33, with the single large port 36, is that at the conclusion of each firing stroke, the compression or firing chamber is adequately cooled before another compression and ignition of the charge is brought about.

What is claimed is:—

In an internal combustion engine, a crank case having a worm chamber and provided with an oil outlet leading from the chamber to the interior of the crank case, a cylinder on the crank case, a cap on the cylinder and having an extension prolonged into the cylinder and spaced from the inner cylinder wall, a single sleeve valve journaled in the cylinder and extended at one end into the space between the inner cylinder wall and the outer surface of the extension, the inner surface of said end of the valve being in direct contact with the outer surface of the extension, and the outer surface of the valve being in direct contact with the inner cylinder wall, the valve having a port and being provided on its outer surface with oil-holding grooves disposed about the port, the valve being supplied on its inner surface with end and intermediate sets of circumferential grooves located on opposite sides of the said oil-holding grooves, the valve being equipped on its outer surface with a spiral groove extended from the intermediate set of circumferential grooves to the worm chamber, a conduit having one end in communication with the interior of the crank case, the opposite end of the conduit discharging between the inner

wall of the cylinder and the outer surface of the valve and into the end set of circumferential grooves, the valve having a transverse opening in the midst of the end set of grooves and carrying oil from the last-specified end of the conduit to the inner surface of the valve and the outer surface of the extension, the conduit having a branch discharging on the intermediate set of circumferential grooves and having another branch that discharges into the worm chamber, means for forcing oil from the crank case through the pipe to the conduit, a worm wheel on the valve, and a worm meshing with the worm wheel and located in the worm chamber.

In testimony that I claim the foregoing as my own, I have hereto affixed my signature.

EDWARD E. THISLER.
